UNITED STATES PATENT OFFICE.

OLIVER S. JENNINGS, OF BROOKLYN, NEW YORK, ASSIGNOR TO WESTINGHOUSE ELECTRIC & MANUFACTURING COMPANY, A CORPORATION OF PENNSYLVANIA.

SAFETY SWITCH.

Application filed September 8, 1920. Serial No. 408,879.

To all whom it may concern:

Be it known that I, OLIVER S. JENNINGS, a citizen of the United States, and a resident of Brooklyn, in the county of Kings 5 and State of New York, have invented a new and useful Improvement in Safety Switches, of which the following is a specification.

My invention relates to switches and particularly to enclosed cut-out switches of the safety type wherein the switch elements are enclosed within a housing and protected by a movable cover which is retained in closed position so long as the switch is included in 15 a closed circuit.

One object of the invention is to provide a simple, inexpensive and reliable switch mechanism wherein the switch-operating lever is provided with a simple interlocking 20 device capable of retaining the cover in closed position when the switch is closed and releasing the cover when the switch is moved to open position.

Another object is to provide a switch 25 mechanism having the above characteristics wherein the switch cannot be closed so long as the cover is open, and wherein the closing movement of the cover returns the interlocking device to a position permitting movement of the operating lever to closed position.

Briefly, the invention resides in a simple 30 interlocking device which may be mounted upon the axle of a round-bar operating lever of a well-known type and which consists of a segmental disc mounted upon the axle of the operating lever and having its curved peripheral edge concentric with the axis of rotation. One end of the disc is slotted radially and fits into a portion of the axle which is formed at the point of connection with straight parallel sides. This arrangement prevents relative rotary movement of the disc and axle but permits a radial movement 35 of the disc with respect to the axle. The curved peripheral edge of the segmental disc is provided with a flange which is bent normal to the plane of the disc and registers with a clip carried by the cover when the operating lever is in closed position. This flange, however, clears the clip when the disc is moved, by the operating lever, into open position and permits the door to be opened by radial displacement of the disc 50 caused by the spring normally tending to

move the disc away from the axle of the operating lever. Radial movement of the disc is controlled by a slot-and-pin mechanism which permits movement of the disc radially until the operating lever is moved to 60 open position. When the disc moves radially and opens the cover, one edge thereof engages the cover and prevents movement of the operating lever to closed position so long as the cover remains in open position. 65

Closing movement of the cover returns the disc to a position wherein the operating lever is free to move to closed position.

The details of the construction and the advantages incident to the novel arrangement will be apparent upon reference to the accompanying drawings forming a part of the application, wherein:—

Figure 1 is a plan view of the switch mechanism showing the cover and switch in 75 closed position.

Fig. 2 is a longitudinal vertical section of the apparatus shown in Fig. 1, taken on the line II—II of Fig. 1.

Fig. 3 is a transverse vertical section of 80 the housing taken on the line III—III of Fig. 2.

Fig. 4 is an elevational view of a latch clip for retaining the cover in closed position, 85

Fig. 5 is an elevational view of an interlocking disc.

Referring to the drawings, the apparatus includes a housing or cabinet 5 provided, adjacent to one end, with a permanent cover portion 6 having a movable cover or door 7 hinged thereto upon a hinge 8 which extends transversely of the cabinet. The cover 7 is yieldingly retained in closed position by means of a spring clip 8' that is secured to the cover and which snaps into a recess 8a provided in the end wall 5. 90

The switch panel 9 is fastened to the bottom 10 of the housing and consists of a porcelain base 11 upon which is mounted a pair of switch pivot jaws 12, each carrying a switch-blade member 13 and adapted to be moved into and out of engagement with the contact-terminal jaws 14. The panel also includes a pair of fuses 15 of the screw-plug type which are mounted in suitable receptacles 16 and are adapted to be cut off from the live terminals when the switch blades are in open position. The fuses and switch-blade members are so located that 100 105 110

they are accessible through the opening in the housing for the purpose of inspection and renewal of the fuse, when required, and it is a purpose of this invention to so interlock the movable cover or door, which closes the opening in the housing, that access to the interior thereof may not be gained until the switch has been moved to open position or until the current to the fuse receptacles and accessible parts of the switch has been cut off.

The switch-blade members 14 are actuated by an operating handle or lever which consists of a one-piece round iron bar 17 provided, at one end, with a loop or eyelet 18 which serves as a handle. The bar projects through a bearing 18' provided in one side of the housing and is so bent as to provide the crank shaft 19 which is slipped through an eyelet 20 secured to the switch-blade connecting bar 21.

It will be seen from the foregoing that counterclockwise movement of the operating handle moves the switch-blade members out of engagement with the contact members, the extreme limit of movement being indicated by dot-and-dash lines in Fig. 2.

The axle 22 of the operating lever 17 is located beneath the cover hinge 8 and is so notched at 23 as to provide a short section having straight parallel sides. A segmental disc 24, which is provided with a straight radially disposed slot 25, is slipped over the notched section of the axle, the sides of the slot so engaging the straight sides of the axle as to prevent relative rotary movement of the disc with respect thereto but permitting relative radial displacement of the disc with respect to the operating lever. The disc is further provided with an angularly disposed slot having a radially disposed wing 26 and a concentrically disposed wing 27. This slot is adapted to receive a guide pin 28 which is secured to the side of the housing and prevents radial movement of the disc except when the disc is moved in a position wherein the wing 26 of the angular slot registers with the pin 28. The spring 29, which is attached to the disc at a point adjacent the axle and at the other end to a pin 28, serves to normally exert a force upon the disc tending to move it radially away from the axle. Such radial displacement of the disc is prevented, however, so long as the pin is registered with the concentric slot 27. The cover or door 7 is provided, on its lower side adjacent the hinge, with a latch clip 30 having a flange 31 projecting toward the adjacent side of the housing. A portion of the curved peripheral edge of the disc 24 is provided with a flange 32 projecting toward the latch clip, and the latch clip 30 and the disc or movable latch member 24 are so relatively positioned that, when the disc occupies the position, indicated in Fig. 2,

wherein the switch is in closed position, the flanges 31 and 32 overlap and prevent opening movement of the cover.

When the operating lever is moved to open position, wherein the switch-blade members are withdrawn a safe distance from their respective contact jaws, the disc 24 occupies the position indicated in dotted lines in Fig. 2, wherein the flange 32 of the disc 24 occupies a position out of registry with the flange 31. At such time, the door is free to be moved to open position, and the radial slot 26 registers with the pin 28. The spring 29 causes radial movement of the disc 24 into engagement with the under side of the door and thereby forces the door into open position the moment the clip 30 is released, the disc occupying, after such movement, the position indicated by dot-and-dash lines in Fig. 2. When the disc is in its raised position, closing movement of the operating lever is prevented by reason of the engagement of the wall of the slot 26 with the pin 28. The switch cannot, therefore, be closed so long as the disc remains in its raised position. When the door is moved to closed position, the disc 24 is depressed into the position indicated in dotted lines in Fig. 2, in which position the disc will permit clockwise rotation of the operating lever to closed position.

From the foregoing it will be seen that, when the switch is in closed position, the door cannot be opened, and the door may be opened when the switch has been moved a safe distance from the contact jaws. It will also be seen that the switch can not be closed until after the door has been closed. It is not possible, therefore, to gain access to the live switch elements or circuits so long as the switch is in closed position.

While I have described and illustrated but one embodiment of my invention, it will be apparent to those skilled in the art that various changes, modifications, substitutions, additions and omissions may be made in the apparatus described without departing from the spirit and scope of the invention, as set forth by the appended claims.

I claim as my invention:

1. A switch mechanism comprising a housing having an opening therein, a movable cover for closing the opening, a movable switch within the housing, a rotatable operating lever for moving the switch to open and to closed positions, and a latching member for the cover mounted for rotation about the axis of rotation of the operating lever and rotatable with the operating lever for preventing movement of the operating lever to closed position so long as the cover is in open position and movable by the cover into a position permitting closing movement of the operating lever when the cover is in closed position.

2. A switch mechanism comprising a housing having an opening therein, a movable cover for closing the opening, a movable switch within the housing, a rotatable operating lever for moving the switch to open and to closed positions, and latching means for the cover mounted for rotation about the axis of rotation of the operating lever and rotatable with the operating lever for preventing movement of the operating lever to closed position so long as the cover is in open position and movable by the cover into a position permitting closing movement of the operating lever when the cover is in closed position, the said latching means being adapted to engage the cover and retain it in closed position when the operating lever is in closed position.
3. A switch mechanism comprising a housing having an opening therein, a movable cover for closing the opening, a movable switch within the housing, a rotatable operating lever for moving the switch to open and to closed positions, and latching means for the cover mounted for rotation about the axis of rotation of the operating lever and rotatable with the operating lever and movable in a radial direction for preventing movement of the operating lever to closed position so long as the cover is in open position and movable radially by the cover into a position permitting closing movement of the operating lever when the cover is in closed position.
4. A switch mechanism comprising a housing having an opening therein, a movable cover for closing the opening, a movable switch within the housing, a rotatable operating lever for moving the switch to open and to closed positions, a latching means for the cover mounted for rotation about the axis of rotation of the operating lever and rotatable with the operating lever and movable in a radial direction for locking the switch in open position and adapted, when the lever is in closed position, to retain the cover in closed position and, when the lever is in open position, to permit opening movement of the cover, and means for automatically moving the latching member radially to locking position after the cover has moved to open position.
5. A switch mechanism comprising a housing having an opening therein, a movable cover for closing the opening, a movable switch within the housing, a rotatable operating lever for moving the switch to open and to closed positions, a latching member for the cover mounted for rotation about the axis of rotation of the operating lever and rotatable with the operating lever and movable in a radial direction for locking the switch in open position and adapted, when the lever is in closed position, to retain the cover in closed position and, when the lever is in open position, to permit opening movement of the cover, and means for automatically moving the latching member radially to locking position after the cover has moved to open position.
6. A switch mechanism comprising a housing having an opening therein, a movable cover for closing the opening, a movable switch within the housing, a rotatable operating lever for moving the switch to open and to closed positions, a latching member for the cover mounted for rotation about the axis of rotation of the operating lever and rotatable with the operating lever and movable in a substantially radial direction for locking the switch in open position and adapted, when the operating lever is in closed position, to retain the cover in closed position and, when the operating lever is in substantially open position, to permit opening movement of the cover, and means for automatically moving the latching member radially to locking position after the cover has moved a predetermined distance toward open position.
7. A switch mechanism comprising a housing having an opening therein, a movable cover for closing the opening, a movable switch within the housing, a rotatable operating lever for moving the switch to open and to closed positions, a latch clip mounted upon the cover, a latch member mounted for rotation about the axis of rotation of the operating lever and rotatable with the operating lever and movable radially and provided with a flange adapted to register with the latch clip when the operating lever is in closed position and to prevent opening movement of the cover and to clear the said clip when the operating lever is moved to open position, means normally tending to move the latch member radially to prevent rotary movement of the operating lever while the cover is raised, and means preventing radial movement of the latch member until after the operating lever has moved substantially into open position.
8. A switch mechanism comprising a housing having an opening therein, a movable cover for closing the opening, a terminal, a switch within the housing to be moved into and out of engagement with the terminal, a rotatable operating lever movable to open and to closed positions for moving the switch to open and to closed positions, respectively, a latch clip carried

2

by the cover, a latch plate rotatable with the operating lever and movable radially with respect thereto for locking the switch in open position and provided with a flange adapted, when the operating lever is in closed position, to register with the said clip and prevent opening movement of the cover and, when the operating lever is in open position, to clear the said clip, a guide pin mounted on the housing, the said latch plate being provided with an angular slot having one wing radially disposed and the other wing concentrically disposed with respect to the axis of the operating lever, through which the said pin projects, a spring attached, at one end, to the plate and, at the other end, to the housing whereby the plate is moved radially when the radial slot is moved into registry with the said pin, and means for moving the said radial slot into registry with the pin when the operating lever has moved to open position to permit radial movement of the said plate.

10

In testimony whereof, I have hereunto subscribed my name this twenty-seventh day of August, 1920.

OLIVER S. JENNINGS.
